UNITED STATES PATENT OFFICE

168,713

HOLDER FOR BEVERAGE GLASSES

Noah Rubin, New York, N. Y.

Application July 22, 1952, Serial No. 20,711

Term of patent 14 years

(Cl. D44—7)

To all whom it may concern:

Be it known that I, Noah Rubin, a citizen of the United States, residing in New York city, county and State of New York, have invented a new, original, and ornamental Design for Holder for Beverage Glasses, of which the following is a specification, reference being had to the accompanying drawing, forming a part thereof, in which:

Fig. 1 is a top plan view of a holder for beverage glasses, showing my new design;

Fig. 2 is a vertical cross-sectional view taken along line 2—2 of Fig. 1; and

Fig. 3 is a perspective view thereof.

I claim:

The ornamental design for a holder for beverage glasses, as shown.

NOAH RUBIN.
